(57) **CLAIM**

The ornamental design for an electric grinder, as shown and described.

DESCRIPTION

FIG. 1 is a perspective view of an electric grinder showing the new design.

FIG. 2 is a front view of the electric grinder of FIG. 1.

FIG. 3 is a rear view of the electric grinder of FIG. 1.

FIG. 4 is a side view of the electric grinder of FIG. 1.

FIG. 5 is an opposite side view of the electric grinder of FIG. 1.

FIG. 6 is a top view the electric grinder of FIG. 1; and,
FIG. 7 is a bottom view the electric grinder of FIG. 1.

The dash-dash broken lines are shown for the purpose of illustrating parts of the electric grinder that form no part of the claimed design. The dash-dot-dash broken line in FIG. 7

(Continued)

depict the boundary of the bottom surface of the electric grinder that form no part of the claimed design.
